IRONING MACHINE

Edward B. Carson, Fort Myers, Fla.

Application July 16, 1936, Serial No. 90,911

9 Claims. (Cl. 38—60)

This invention relates to ironing machines, and has to do with an ironing machine intended for domestic use.

Among the objects of my invention are the provision of an ironing machine of simple and inexpensive construction, which comprises relatively few parts, is of comparatively light weight, may be mounted upon a door, wall, or other suitable support, and the operation of which may be controlled with expedition and facility. Further objects and advantages will appear from the detail description.

In the drawings:

Figure 1 is a plan view of an ironing machine embodying my invention;

Figure 2 is a front view of the ironing machine, partly broken away;

Figure 3 is a sectional view, on an enlarged scale, taken substantially on line 3—3 of Figure 1, partly broken away, certain parts being shown in elevation, and the shoe, shoe shaft and associated parts being omitted for clearness of illustration;

Figure 4 is a fragmentary sectional view on an enlarged scale, taken substantially on line 4—4 of Figure 1, parts being broken away and certain parts being shown in elevation;

Figure 5 is a fragmentary sectional view, on an enlarged scale, taken substantially on line 5—5 of Figure 2, the roll being shown fragmentarily and in end view;

Figure 6 is a fragmentary sectional view through the stripping plate supporting rod and associated parts, on an enlarged scale, taken substantially on line 6—6 of Figure 1, certain parts being shown in elevation;

Figure 7 is a view, partly in section and partly broken away, taken substantially on line 7—7 of Figure 1, showing the roll in end view and the shoe supporting arm released in raised position;

Figure 8 is an end view of the ironing machine, looking at the shoe operating lever end thereof, with the housing for this lever and associated parts removed;

Figure 9 is an end view of the ironing machine, looking at the motor end thereof, partly broken away and in section;

Figure 10 is a fragmentary sectional view, on an enlarged scale, taken substantially on line 10—10 of Figure 9, certain parts being shown in elevation; and

Figure 11 is an isometric view of a closet and the door thereof in opened position, illustrating the application of my machine to the closet door.

The ironing machine of my invention com-

prises a frame 15 having a bight portion 16 and arms 17 and 18 extending forwardly from the ends thereof, this frame being of substantially U-shape in plan. Preferably, frame 15 is formed in a single piece from sheet metal plate of suitable gauge, by stamping and bending operations, though it may be formed in any other suitable or preferred manner.

An exteriorly threaded bushing 19, provided at its outer end with an exterior flange 20, is inserted through arm 18 of the frame and clamped thereto by means of a clamping nut 21 screwing upon the body of the bushing and cooperating with flange 20. Bushing 19 is disposed coaxially with sleeve 22 of a cup-shaped member 23 provided, at its outer end, with a circumferential flange 24 suitably secured, conveniently by spot welding, to arm 17 at the inner face thereof. A bushing 25, which is preferably a graphite filled bushing of known type, is mounted in sleeve 22. A roll shaft 26, rotatably mounted in bushings 19 and 25, projects beyond the latter bushing, and has its adjacent outer end portion shaped to provide a squared stud 27. This stud fits into a coupling member 28 secured thereon in a suitable manner, as by means of a set screw 29. Member 28 is provided, at its outer end, with projections 30 disposed between projections 31 of a similar and oppositely disposed coupling member 32, there being a felt cushioning member 33 disposed between the projections of the coupling members. This provides a flexible coupling between the roll shaft 26 and the associated drive shaft therefor, hereinafter referred to. The coupling is of known type and need not be illustrated nor described in greater detail. While this particular form of coupling is preferred, any other suitable or preferred coupling may be used. It will be noted that the member 23 accommodates the coupling member 28 and reduces the length of the coupling extending outward beyond arm 17 of frame 15, which is conducive to compact arrangement of parts.

An electric motor 34 is mounted, by means of a bracket 35, on the outer face of arm 17 of the frame. This motor has driving connection, through an associated speed reduction unit 36, to a stub shaft 37 which fits into coupling member 32, the latter being secured to stub shaft 37 by a set screw 38. The electric motor 34 and the associated unit 36 are built together, constituting a power and speed reduction unit, are of known construction, and need not be described nor illustrated in greater detail. This provides

simple and highly efficient means for driving the roll shaft 26, which shaft is driven in a clockwise direction as viewed in Figure 8.

An ironing roll 40 is mounted upon shaft 26 for rotation therewith. This roll is, in general, of known construction and comprises a sheet metal cylindrical body 41 within which, adjacent each end of the body, are secured cup-shaped sheet metal heads 42 and 43. A relatively thick collar 44 is secured to the outer face of head 42, centrally thereof, conveniently by spot welding, this collar and head 42 being provided with aligned openings which accommodate shaft 26. Head 43 is also provided, at its outer face, with a relatively thick collar 45 spot welded thereto and provided, at its outer end, with a diametrical slot 46 which receives a key 47 secured through shaft 26. In this manner roll 40 is keyed to shaft 26 for rotation therewith and is held against endwise movement by contact of the collars 44 and 46 with sleeve 22 and bushing 19, as will be clear from Figure 3. The roll 40 is provided with a fabric pad and covering 48, of known type, as is usual.

A shoe shaft 50 is rockably mounted through arms 17 and 18 of frame 15, in back of roll 40 and spaced from bight element 16 of the frame. An arm 51 is secured on shaft 50, conveniently by means of a taper pin 52, midway between arms 17 and 18 of the frame. Arm 51 extends at an upward and forward inclination from shaft 50 and is slotted from its upper end, at 53. A shoe supporting arm 54, of channel cross-section, straddles arm 51 and is loosely mounted at its lower end upon shaft 50. Bight element 55 of arm 54 is provided with a lengthwise slot 56, shown more clearly in Figure 7, which receives the reduced and threaded outer portion 57a of a headed screw 57, body 57b of which provides, at its outer end, a shoulder for contact with the inner face of bight element 55. A clamping nut 58, preferably knurled as shown, threads upon the screw 57 at the outer face of the element 55. Normally, arm 54 is in lowered position with bight element 55 seating upon the upper face of arm 51 and the body 57b of screw 57 engaged in slot 53 of arm 51, with the nut 58 turned into tight contact with bight element 55, thus clamping the two arms together for movement as a unit, as in Figures 9 and 10. The upper end of arm 54 extends between two ears 59 projecting from the rear face of a shoe 60, and is pivoted thereto by a pin 61. The forward face of shoe 60 is concaved to fit the curvature of roll 40, with which the shoe cooperates in a known manner, and the shoe is moved to and from the roll, when the arms 51 and 54 are secured together, by rocking of shaft 50 in an appropriate manner.

Slot 56 extends beyond the upper end of slot 53 of arm 51 such a distance that screw 57 may be completely disengaged from the latter arm, thus permitting arm 54 to be turned about shaft 50 independently of arm 51. In Figure 7 arm 54 is shown as disengaged from arm 51 and turned into substantially vertical position, the shoe 60 being turned about the axis of pin 61 into substantially horizontal position so as to give ready access to the concaved ironing surface of the shoe for cleaning and polishing of such surface, or other purposes. In the event the frame 15 is mounted upon a supporting surface, indicated by the dot and dash line S-S of Figure 7, such as to prevent turning of the shoe 75 into the substantially horizontal position shown

in full lines, the shoe may be turned into the inclined position indicated by dot and dash lines so as to render readily accessible its ironing surface. In Figure 7 arm 51 is shown in full lines in the position which it occupies when shaft 50 has been turned counterclockwise for moving shoe 60 away from roll 40 and the position of this arm, when shaft 50 has been turned clockwise for moving the shoe to the roll, as in Figure 9, is indicated by the dot and dash lines. Shoe shaft 50 projects outward beyond arm 18 of frame 15 and this projecting end portion of the shaft is flattened at 62, as shown in Figure 1. A shoe operating arm 63 of channel cross section, as will be clear from Figures 1, 4 and 8, is secured upon the flattened end portion of shaft 50 and is confined between arm 18 of the frame and a cotter pin 64 inserted through shaft 50 adjacent the end thereof. A collar 65 is secured on shaft 50 in contact with the inner face of frame arm 18, by means of a set screw 66, this collar cooperating with arm 18 and arm 63 to hold shaft 50 against endwise movement. An operating rod 67 passes loosely through bight element 63a of arm 63, adjacent the lower end thereof, and has a nut 68 secured upon its rearward end and contacting the rearward face of an outwardly bulged rounded element 63b of bight element 63a. A coil compression spring 69 is mounted about rod 67 and confined between the forward face of bight element 63a and a washer 70 adjustable on rod 67 by means of a nut threaded upon the rod and held in adjustment thereon by means of an associated jam nut 72. This provides means for moving the shoe 60 into contact with the roll 40 and maintaining it in contact therewith under spring pressure upon rearward endwise movement of rod 67.

The forward end of rod 67 is slotted and has secured therein in a suitable manner, conveniently by welding, a finger 73 projecting rearward from a cam yoke 74. Conveniently, yoke 74 is of laminated construction, comprising three plates suitably secured together, by welding or otherwise and finger 73 projects from the central plate. The yoke may be constructed in any other suitable or preferred manner.

Yoke 74 defines a square frame within which is disposed a cam 75 so shaped as to maintain contact with the four sides of the yoke, as in Figure 4, so as to avoid any objectionable looseness between the yoke and the cam. Cam 75 is provided with an integral hub 76 which, together with the cam, is mounted to turn upon a stub shaft 77 secured through arm 18 of frame 15. This stub shaft is provided, adjacent its inner end, with a shoulder 78 contacting the outer face of arm 18 and cooperating with a nut 79, screwing upon the inner end of shaft 77 at the inner face of arm 18, for securing the stub shaft to the arm. Two washers 80 and 81 are disposed about stub shaft 77 and hub 76 of cam 75, respectively, at the inner side and the outer side of yoke 74 and serve to maintain the latter and cam 75 in proper relative positions, axially of stub shaft 77. Cam 75 and hub 76 thereof are confined against outward movement along stub shaft 77 by a washer 82 mounted upon the shaft and confined between the outer end of hub 76 and a cotter pin 83 secured through stub shaft 77. A collar 84 is secured upon the outer portion of hub 76, by means of a set screw 85 and is provided with a recess which snugly receives the lower end of a shoe 75

operating lever 86 upon the upper end of which is secured a knob 87.

When the lever 86 is in the position shown in Figure 8, the cam 75 occupies the position shown 5 in Figure 4, at which time the shoe 60 is held in contact with roll 40 by pressure exerted through the compression spring 69, cam 75 being on dead center with stub shaft 77 and rod 67 effective to hold the shoe in such position. By 10 turning lever 86 clockwise, as viewed in Figure 8, with corresponding turning of cam 75 so as to move yoke 74 toward the left, shoe shaft 50 is turned clockwise a proper distance for moving shoe 60 away from roll 40 out of contact there- 15 with.

A motor control switch 88, of known type, is suspended from the top wall of a box-like housing 89 secured to frame 15, conveniently by welding, at the inner face of bight element 16 and arm 17 thereof. This switch comprises a switch lever 90 which is yieldingly urged toward circuit opening position, this lever being shown in closed circuit position in Figure 9. It will be understood that current is supplied to motor 34 by means of an 20 electric cord enclosing conductors having appropriate connections to the switch 88 and the motor, this cord being provided with the usual plug cap for connection to a lighting or other suitable circuit, by means of the usual plug.

30 A switch control arm 91 is secured upon shoe shaft 50 by means of a set screw 92. Arm 91 is so disposed that it contacts switch lever 90 and moves the latter into the closed circuit position shown in Figure 9 when shaft 50 is turned clockwise, as viewed in this figure, into position to hold shoe 60 in cooperating relation to roll 40. When shaft 50 is turned counterclockwise into position to hold shoe 60 out of contact with roll 40, arm 91 releases the switch lever 90, which is then moved 35 into circuit opening position, this resulting in opening the motor circuit and stopping the drive of roll 40. The shoe operating lever 86 thus provides, in conjunction with shoe shaft 50 and associated parts, means whereby the shoe may be moved to and from the roll and the roll drive is enabled and disabled in accordance with movement of the shoe to and from the roll. This eliminates possibility of burning of the roll cover due to contact between the hot shoe and the roll 40 without rotation of the latter, and also avoids unnecessary operation of the motor, with resulting conservation of electrical energy, while providing simple and highly efficient means for controlling operation of the machine.

50 The shoe 60 is of known type and is heated by means of electrical resistance elements or heating means, in the known manner. The circuit of the heating element is controlled by a switch 93, of known type, supported by a bracket 94 welded or otherwise suitably secured to arm 17 of frame 15, at the front thereof. It will be understood that electrical energy may be supplied to the heating element of shoe 60, through switch 93, by means of suitable connections to the conductors of the 55 electric cord previously referred to. Suffice it to state that electrical energy may be supplied to the heating element of shoe 60 and that the switch 93 provides means for controlling such supply of energy.

70 A rod 95, shown more clearly in Figures 2 and 6, is mounted in arms 17 and 18 of frame 15, beneath roll 40 and in rear of roll shaft 26. A spacing collar 96 is secured upon rod 95, by a pin 97, and contacts the inner face of arm 18, as shown 75 in Figure 6. The end of rod 95, projecting out-

ward beyond arm 18, is threaded and receives a nut 98 which cooperates with collar 96 for confining shaft 95 against endwise movement in either direction and, if desired, for clamping the rod to arm 18 in such manner as to secure it against rotation. Preferably, however, collar 96 is provided, in its outer end, with a lengthwise bore which receives a pin 99 secured in arm 18 and effective for positively holding rod 95 against rotation.

10 A sheet metal stripping plate 100 is shaped at its lower portion to provide a sleeve 101 which fits loosely about rod 95. This plate is confined against endwise movement between collar 96 and a collar 102 mounted upon rod 95 at the inner 15 face of arm 17 of frame 15. Plate 100 is provided with a central slot 103 which accommodates a leaf spring 104 the lower end portion of which is bent about rod 95 and secured thereto by means of a screw 105, or in any other suitable manner. At its upper end, spring 104 bears against the rearward face of plate 100 and holds the upper edge thereof in contact with the roller 40, this edge of the plate being beveled and the plate being inclined upward and contra to the direction 20 of rotation of the roller, as in Figure 5. Plate 100 serves to remove from the roller 40 articles which adhere thereto due to the presence of starch, or other causes, thus preventing possibility of wrapping articles about the roller. While the use of 30 this plate may not be essential in all cases, it is preferred, though it may be omitted if desired.

The machine illustrated and above described is of compact construction, has relatively few parts, and is of comparatively light weight. This machine does not require the use of a supporting 35 table or stand and it may be mounted upon a door, wall, or other suitable support, by means of the U-shaped frame 15. To facilitate mounting of the machine in this manner I provide bight 40 element 16 of frame 15 with keyhole slots 106 adapted for reception of round headed screws 107 secured in a support 108. Preferably, the slots 106 are disposed adjacent the end portions 45 of frame 15 and the top portion of bight element 16, as will be clear from Figures 3 and 9. Bight element 16 seats flat against the support 108 and, in conjunction with screws 107, serves to support the machine to best advantage while permitting ready removal thereof if necessary or 50 desired.

55 Preferably, I provide a sheet metal box-like housing 110 which encloses the shoe operating arm 63, rod 67, cam yoke 74, cam 75, and associated parts. This housing is suitably secured to arm 18 of frame 15, as by means of screws 111 passing through the top and the bottom walls of the housing and threading into the upper and the lower edges of arm 18. Housing 110 is provided with a slot 112 through its top and front walls, 60 which slot accommodates the shoe operating lever 86 and may limit turning thereof in either direction. Lever 86 fits snugly into collar 84, as previously stated, and may be withdrawn therefrom for removing or replacing housing 110, this 65 lever being replaced, when the housing is in position, by inserting it through slot 112 into the collar 84. The rear wall of housing 110 may be open to accommodate rearward movement of rod 67 and the shoe operating arm 63, as will be understood from Figure 1, in which the housing, in its normal position, is indicated by dot and dash lines.

70 An ironing machine constructed in the manner herein disclosed and of a size for ironing handker- 75

chiefs, neckties, and analogous articles, is of light weight and may be supported upon a wall, door, or other structure. In Figure 11 I have illustrated an ironing machine embodying my invention, indicated in its entirety by the reference letter I, as mounted upon a door *d* of a closet *c*, the machine being disposed at the inner face of the door so as to be within the closet when the door is in closed position. A machine of this character is particularly suitable for use in 10 barber shops, shoe shine parlors, clothes cleaning and pressing establishments, and other places of like character, where patrons frequently desire to have handkerchiefs, neckties, and other small 15 articles pressed. This machine, when made in larger sizes, suitable for household use, is of comparatively light weight and may be supported upon the house wall by means of screws 107 or equivalent means. This is advantageous, since 20 the machine, supported in this manner, occupies but little space and is immediately available for use as desired. It is known that approximately 90 percent of people using domestic ironing machines 25 keep the machines in the kitchen. Since an ironing machine is used intermittently, and frequently but once or twice a week, it occupies in the kitchen space which at other times could be used to advantage. Various attempts have been made 30 to solve this difficulty, the most successful of which is the cabinet type of ironing machines capable of being used as a table when not being used for ironing. In many small apartments, however, of the kitchenette type, even the cabinet type ironing machine may occupy an objectionable amount of space. I avoid this objection, 35 to a great extent, by supporting the ironing machine of my invention upon the wall or other suitable support, leaving the floor space beneath unobstructed for other purposes, while also having the machine immediately available for use 40 at all times. This I render possible by the use of a frame carrying the cooperating ironing elements and the driving and controlling means therefor, this frame being suitable for mounting 45 upon a door, wall, or other supporting structure constituting a part of the house structure, the machine as a whole being so constructed and of such light weight as to permit of it being supported in the manner stated.

50 What I claim is:

1. In an ironing machine of the character described, a frame of substantially U-shape in plan, a roll shaft rotatably mounted through the arms of said frame, a roll secured on said shaft, a shoe shaft 55 rockably mounted through the arms of said frame, a shoe carried by said shoe shaft for movement to and from said roll, an electric motor mounted on one arm of said frame having driving connection to said roll shaft, said shoe shaft projecting outward beyond the other of said arms, an operating arm secured on said projecting portion of said shoe shaft, a shoe operating lever mounted on said other arm of said frame, and operating connections between said lever and said arm.
- 60 2. In an ironing machine of the character described, a frame provided adjacent each end with a forwardly projecting arm, a roll mounted on said arms, an electric motor mounted on one arm of said frame having driving connection to said roll, a shoe shaft 65 rockably mounted in the arms of said frame and projecting outward beyond the other arm thereof, a shoe supporting arm secured on said shaft and projecting upward therefrom, a shoe carried by said arm for movement to and 70 from said roll, and shoe shaft operating means 75

carried by said other arm of said frame and operatively connected to the portion of said shaft projecting outward beyond said other arm.

3. An ironing machine of the character described, comprising a frame, a roll mounted on 5 said frame, means for rotating said roll, a rod mounted in said frame beneath said roll, a stripping plate mounted on said rod inclined upward toward said roll contra to the direction of rotation thereof, and means cooperating with said 10 rod for yieldingly holding the upper edge of said plate in contact with said roll.

4. An ironing machine of the character described, comprising a frame, a roll mounted on 15 said frame, means for rotating said roll, a rod mounted in said frame beneath said roll and held against turning, a stripping plate loosely mounted on said rod and inclined upward toward said roll contra to the direction of rotation thereof, and a 20 leaf spring secured on said rod and yieldingly holding the upper edge of said plate in contact with said roll, said plate having a slot accommodating said spring.

5. In an ironing machine of the character described, a roll, a rockably mounted shoe shaft, 25 an arm fixed on said shaft and slotted from its free end, a second arm loose on said shaft and having a slotted element overlying the slotted portion of said fixed arm, a shoe mounted on the free end of said second arm, and a headed member 30 slidably lengthwise of said second arm extending through the slots of said arms and securing the latter together for movement as a unit, said member being movable along the slot of said second arm into position to release the latter 35 from said fixed arm.

6. In an ironing machine of the character described, a roll, a rockably mounted shoe shaft, 40 an arm fixed on said shaft and having a slot open at one end, a second arm of channel cross-section straddling said fixed arm and loose at one end on said shaft, a shoe mounted on the other end of said second arm for cooperation with said roll, the bight element of said second arm having a lengthwise slot therethrough extending beyond the free end of said fixed arm, a headed screw 45 extending through the slot of said second arm and adjustable therealong into and out of engagement with the slotted portion of said fixed arm, the outer portion of said screw being of reduced diameter providing a shoulder thereon at the inner face of the bight element of said second arm, and a clamping nut threaded upon said screw at the outer face of said bight element.

7. In an ironing machine of the character described, a frame provided adjacent each end with a forwardly projecting arm, a roll supported by 55 said arms, an electric motor mounted on one arm of said frame having driving connection to said roll, a shoe shaft rockably supported by the arms 60 of said frame, a shoe supported by said shaft for movement to and from said roll, and shoe shaft operating means carried by the other arm of said frame and operatively connected to said shoe shaft.

8. In an ironing machine of the character described, a frame provided adjacent each end with a forwardly projecting arm, two cooperating ironing members mounted on the arms of said frame for relative movement one toward and away from the other, one of said members being a roll, an 70 electric motor mounted on one arm of said frame having driving connection to said roll, and operating means mounted on the other arm of said frame having operating connection to one of said 75

members effective for moving it toward and away from the other of said members.

9. In an ironing machine of the character described, a frame of approximately U-shape in plan comprising a substantially flat bight portion and arms projecting forwardly from said bight portion adjacent the ends thereof, two co-operating ironing members mounted on said arms of said frame, one of said members being a roll

and the other of said members being movable toward and away from said roll, an electric motor mounted on one arm of said frame having driving connection to said roll, and operating means mounted on the other arm of said frame having operating connection to said other member effective for moving the latter toward and away from said roll. 5

EDWARD B. CARSON.
